DISPOSAL UNIT

Loren A. Welches, 251 Medburn St., Concord, Calif.

Filed July 18, 1958, Ser. No. 749,351

4 Claims. (Cl. 241—46)

This invention relates to a disposal unit.

The object of the invention is to provide a disposal unit which is adapted to be used for disintegrating or cutting up articles or materials such as articles which would normally clog up or stop up a toilet.

Another object of the invention is to provide a disposal unit which can be used for disintegrating or disposing of articles such as sanitary napkins, and wherein the disposal unit of the present invention includes a cutting mechanism which is actuated or controlled by the opening or closing of a door so that when the door of the device is opened to place articles therein, the cutting mechanism is automatically turned off, and when the door is closed, the cutting mechanism is automatically turned on, so that the device can be used or operated with increased safety or facility.

A further object of the invention is to provide a disposal unit which is extremely simple and inexpensive to manufacture.

Other objects and advantages will be apparent during the course of the following description.

In the accompanying drawings, forming a part of this application, and in which like numerals are used to designate like parts throughout the same.

Figure 1 is a perspective view of the disposal unit of the present invention.

Figure 2 is an enlarged sectional view taken on the line 2—2 of Figure 1.

Figure 3 is a fragmentary perspective view illustrating certain constructional details of the present invention.

Figure 4 is a sectional view taken on the line 4—4 of Figure 1.

Figure 5 is a fragmentary sectional view illustrating the cutting blades.

Referring in detail to the drawings, the numeral 10 designates or indicates the disposal unit of the present invention, and the disposal unit 10 includes a hollow housing which is indicated generally by the numeral 11. The housing 11 includes a cylindrical side wall 12 which is provided with an elongated opening 13 therein. The numeral 14 indicates a door which is mounted for movement into and out of opened and closed relation with respect to the opening 13, and the door 14 is pivotally or hingedly connected to the wall 12 by means of a hinge unit 15 which has a spring 16 arranged in engagement therewith. The spring 16 serves to normally urge or maintain the door 14 in closed position. A handle 17 is connected to the door 14 and the handle 17 is adapted to be manually gripped in order to facilitate opening of the door 14 as for example when articles are placed in the unit to be chopped up or disposed of.

Mounted within the housing 11 are brackets 18, and the numeral 19 indicates a driven shaft which is supported by the brackets 18.

Arranged in the housing 11 is a plurality of stationary blades or knives 20, and mounted for coaction with the stationary blades 20 are movable blades 21, and the

2

blades 21 are driven by the shaft 19. The numeral 22 indicates a drive shaft which is pivotally connected to the upper end of the shaft 19 by means of a universal coupling 23.

There is further provided a link means which connects the door 14 to the shaft 22, and this link means comprises a first arm 24 which is connected to the door 14 as at 25. A loop 26 is arranged on the other end of the arm 24. The numeral 27 indicates a second arm which is arranged contiguous to the first arm 24 and which is slidably connected thereto, and one end of the arm 27 is loosely connected to the shaft 22 as at 28, while the other end of the arm 27 is provided with loops 29 that slidably receive the arm 24.

Mounted on the upper end of the shaft 22 is a first gear 30, and the gear 30 is mounted for movement into and out of meshing engagement with a second gear 31. The gear 31 is mounted on the lower end of a stub shaft 32, and a motor 33 is provided for rotating or actuating the shaft 32. The motor 33 is supported on a horizontally disposed platform 34, and a dome-shaped casing 35 is arranged above the motor 33. The numeral 36 indicates an "On" and "Off" switch which is adapted to be used for controlling actuation of the motor 33, and wires 37 are provided for supplying electrical energy from a suitable source of supply to the motor 33.

As shown in Figure 2 for example, a conduit 38 is connected to the housing 11, whereby water from a suitable source of supply can be supplied to the interior of the housing. A fitting 39 is connected to the lower end of the housing 11, and a conduit 40 is connected to the fitting 39 in any suitable manner, as for example by means of bolt and nut assemblies 41. The conduit 40 can lead to any suitable location such as to a sewer line whereby the material which has been disintegrated or chopped up can be conveyed through the conduit 40 to any desired or proper location.

As shown in the drawings, the rotary blades 21 may be connected to the shaft 19 in any suitable manner, as for example by means of pins 42, or else a key arrangement may be utilized. The stationary blades 20 are provided with projections 43, which are adapted to coact with similar projections or pointed shoulders 44 on the rotary blades 21, whereby the portions 43 and 44 will coact to help increase the cutting of the articles such as the sanitary napkins.

From the foregoing, it is apparent that there has been provided a disposal unit which is especially suitable for use in disposing of various articles such as sanitary napkins. In use, the unit 10 can be arranged in any convenient location, and the motor 33 can be connected to a suitable source of supply of electrical energy by means of the wires 37. The pipe 38 is adapted to be connected to a water supply and the conduit 40 can lead to a sewer or other locality. Then, when the articles such as the sanitary napkins are to be disposed of, the switch 36 can be turned on so as to actuate the motor 33 and then when an article such as a napkin is to be gotten rid of, the user merely grasps the handle 17 and pulls the door 14 open about the hinge 15. The article is then dropped into the housing 11 and when pressure is released on the handle 17, the spring 16 will return the door 14 to its closed position.

According to the present invention, it will be seen that when the switch 36 is actuated, the motor 33 is turned on so as to continually drive the shaft 32 and gear 31. As long as the parts are in the position shown in Figure 2, the gear 30 will mesh with the gear 31 so that the shaft 22 will rotate to thereby turn the shaft 19 which in turn will rotate the blades 21. However, when the door 14 is opened to insert the articles therein, it will be noted that the arm 24 will be moved a distance until the

loop 26 engages the loop 29 which will then pull the shaft 22 in an outward direction, Figure 2, since the shaft 22 can pivot outwardly by reason of the universal coupling 23. This pivotal movement of the shaft 22 causes the gear 30 to move out of engagement with the gear 31 so that when the door 14 is opened, no further rotation of the shaft 19 and blades 21 will occur. This acts as a safety feature since the cutting blades will not rotate when the door is opened so that there will be no possibility of a person damaging or injuring the hand when inserting articles into the device.

The arm 24 is provided with a shoulder 45, so that when the door 14 closes, the shoulder 45 abuts the adjacent loop 29 so that to return the arm 27 and shaft 22 to the upright position, as for example as shown in Figures 2 and 3. Thus, with the door 14 in closed position, the shoulder 45 will engage or abut the loop 29 so as to maintain the gear 30 in meshing engagement with the gear 31, whereby the cutting mechanism can be operated to disintegrate or chop up the article being disposed of.

The device is constructed so that after the door 14 has been opened, the article to be disposed of can be inserted in the housing 11, and then the door will close so as to cause the blades 21 to rotate whereby the article such as a sanitary napkin can be readily cut up or disintegrated. At the same time, water from the pipe 38 can be used for washing the material down through the housing so that this material will then pass down through the fitting 39 and out through the conduit 40.

The parts can be made of any suitable material and in different shapes or sizes.

The device may be constructed so that when the door is closed, one 360° revolution of the blades 21 is brought about to disintegrate or chop up the article.

With the present invention, bathroom toilets will be prevented from becoming stopped up or clogged up and the device can be used in any desired location. The blades may be provided with sharp cutting edges, and the end portions 43 and 44 serve to help keep the napkins in the proper place when the same are being disposed of or chopped up. The number of blades being used can be varied as desired, and the blades may be arranged in staggered formation. A suitable valve may be utilized in connection with the water inlet pipe 38, and a trap may be provided for the conduit 40. The water may be turned on or off automatically or manually.

The blades such as the blades 21 can be connected to the shaft 19 by pins or else other securing elements such as Allen type screws can be used.

Minor changes in shape, size and rearrangement of details coming within the field of invention claimed may be resorted to in actual practice, if desired.

I claim:

1. In a disposal unit, a hollow housing including a cylindrical side wall, a fitting connected to the lower end of said housing, a conduit connected to said fitting, a spring pressed door hingedly connected to said housing, a handle connected to said door, brackets mounted in said housing, a driven shaft supported by said brackets, a plurality of stationary blades mounted in said housing, a plurality of movable blades operatively connected to said shaft for coaction with said stationary blades, a drive shaft pivotally connected to the upper end of said driven shaft, link means connecting said door to said drive shaft, a first gear on the upper end of said drive shaft, a horizontally disposed platform mounted adjacent the upper end of said housing, a dome-like casing positioned over said platform, a motor supported on said platform below said casing, a stub shaft depending from said motor, and a second gear on the lower end of said stub shaft for selective engagement by said first gear.

said motor, a second gear on the lower end of said stub shaft for selective engagement by said first gear, an inlet fluid conduit connected to said housing, said linkage including a first arm having one end connected to said door and having a loop on its other end, a second arm having one end connected to said drive shaft, said second arm having a loop on its other end slidably receiving said first arm, and a shoulder on said first arm for selective engagement with the loop on said second arm.

10 2. In a disposal unit, a hollow housing, a spring pressed door hingedly connected to said housing, a handle connected to said door, a driven shaft supported in said housing, a plurality of stationary blades mounted in said housing, a plurality of movable blades operatively connected to said shaft for coaction with said stationary blades, a drive shaft pivotally connected to the upper end of said drive shaft, link means connecting said door to said drive shaft, a first gear on the upper end of said drive shaft, a motor supported adjacent the top of the housing, a stub shaft depending from said motor, and a second gear on the lower end of the stub shaft for selective engagement by said first gear.

15 3. In a disposal unit, a hollow housing, a spring pressed door hingedly connected to said housing, a handle connected to said door, a driven shaft supported in said housing, a plurality of stationary blades mounted in said housing, a plurality of movable blades operatively connected to said shaft for coaction with said stationary blades, a drive shaft pivotally connected to the upper

20 end of said driven shaft, link means connecting said door to said drive shaft, a first gear on the upper end of said drive shaft, a motor supported adjacent the top of the housing, a stub shaft depending from said motor, a second gear on the lower end of the stub shaft for selective engagement by said first gear.

25 4. In a disposal unit, a hollow housing, a spring pressed door hingedly connected to said housing, a handle connected to said door, a driven shaft supported in said housing, a plurality of stationary blades mounted in said housing, a plurality of movable blades operatively connected to said shaft for coaction with said stationary blades, a drive shaft pivotally connected to the upper

30 end of said driven shaft, link means connecting said door to said drive shaft, a first gear on the upper end of said drive shaft, a motor supported adjacent the top of the housing, a stub shaft depending from said motor, a second gear on the lower end of the stub shaft for selective engagement by said first gear.

35 5. In a disposal unit, a hollow housing, a spring pressed door hingedly connected to said housing, a handle connected to said door, a driven shaft supported in said housing, a plurality of stationary blades mounted in said housing, a plurality of movable blades operatively connected to said shaft for coaction with said stationary blades, a drive shaft pivotally connected to the upper

40 end of said driven shaft, link means connecting said door to said drive shaft, a first gear on the upper end of said drive shaft, a motor supported adjacent the top of the housing, a stub shaft depending from said motor, a second gear on the lower end of the stub shaft for selective engagement by said first gear.

45 6. In a disposal unit, a hollow housing including a cylindrical side wall, a fitting connected to the lower end of said housing, a conduit connected to said fitting, a spring pressed door hingedly connected to said housing, a handle connected to said door, brackets mounted in said housing, a driven shaft supported by said brackets, a plurality of stationary blades mounted in said housing, a plurality of movable blades operatively connected to said shaft for coaction with said stationary blades, a drive shaft pivotally connected to the upper end of

50 said driven shaft, link means connecting said door to said drive shaft, a first gear on the upper end of said drive shaft, a horizontally disposed platform mounted adjacent the upper end of said housing, a dome-like casing positioned over said platform, a motor supported on said platform below said casing, a stub shaft depending from

55 said motor, and a second gear on the lower end of said stub shaft for selective engagement by said first gear.

60 7. In a disposal unit, a hollow housing including a cylindrical side wall, a fitting connected to the lower end of said housing, a conduit connected to said fitting, a spring pressed door hingedly connected to said housing, a handle connected to said door, brackets mounted in said housing, a driven shaft supported by said brackets, a plurality of stationary blades mounted in said housing, a plurality of movable blades operatively connected to said shaft for coaction with said stationary blades, a drive shaft pivotally connected to the upper end of

65 said driven shaft, link means connecting said door to said drive shaft, a first gear on the upper end of said drive shaft, a horizontally disposed platform mounted adjacent the upper end of said housing, a dome-like casing positioned over said platform, a motor supported on said platform below said casing, a stub shaft depending from

70 said motor, and a second gear on the lower end of said stub shaft for selective engagement by said first gear.
